JENS P. NIELSEN, OF CHICAGO, ILLINOIS

PACKAGE HOLDER

Application filed August 1, 1930. Serial No. 472,259.

The invention relates generally to package holders and more particularly it relates to a holder adapted to retain one or more packages of nails, adhesive or the like within the bore of a roll of sheet material such as tar paper.

In preparing some classes of sheet material such as tar paper for shipment and storage, it is customary to form the material into rolls having a central bore therethrough and it is desirable to supply with each roll a package of nails and a package of adhesive sealing material such as tar. Such packages are usually made of a size which may be slipped into the bore in each roll and various means have been used for holding the packages within the bore.

One form of device used for this purpose comprises spring means made of wire or sheet metal and acting between one side of the bore and the packages to press the packages against the opposite side of the bore.

The general object is to provide a new and improved device of this character which may be economically manufactured and which lends itself to convenient manipulation in placing the packages in the device and in placing the device and the packages in the bore.

30 A further object is the provision of a holder having presser members adapted to bear against opposite sides of the bore and to have one or more packages positioned therebetween, together with means for preventing longitudinal displacement of the packages relatively to the presser members and means acting directly between two presser members to hold the two presser members firmly in engagement with the opposite sides of the bore without exerting undue crushing force upon the packages.

Other objects and advantages will become apparent from the following description taken in connection with the accompanying drawings, in which:

Figure 1 is a front elevational view of a device embodying the invention in its preferred form, the device being shown in operative relation with two packages and some of

the parts being shown in longitudinal section along the line 1—1 of Fig. 3.

Fig. 2 is a view similar to Fig. 1 showing the parts in their inoperative positions ready to receive the packages.

Fig. 3 is a plan view of the device as shown in Fig. 1, with the package 14 removed.

While my invention is susceptible of embodiment in many different forms, I have shown in the drawings and will herein describe in detail one such embodiment, with the understanding that the present disclosure is to be considered as an exemplification of the principles of the invention and is not intended to limit the invention to the embodiment illustrated. The scope of the invention will be pointed out in the appended claims.

In the preferred embodiment chosen for disclosure herein, the holder comprises a pair of elongated, substantially straight presser members 10 and 11, adapted to extend along opposite sides of the bore 12 of a roll (indicated by dotted lines in Figs. 1 and 3), in which position a container 13 of tar and a package 14 of nails or the like may be disposed between the two presser members. The members 10 and 11 are preferably connected together to prevent relative longitudinal displacement thereof and to permit a slight amount of relative transverse movement so that they may be spread apart and pressed into firm frictional contact with the opposite sides of the bore 12. In the present instance the two members 10 and 11 are formed from the same strip of relatively thin gage sheet metal with an integral transverse strut 15 extending between corresponding ends of the two members.

To impart transverse strength to the members 10 and 11 and adapt them for engagement with the curved sides of the bore, each member is preferably made of arcuate cross section as shown in Figs. 1 and 3. At their other or free ends, the presser members are each provided with an end lug 16 bent so as to project inwardly of the bore 12. Thus when the packages 13 and 14 are placed between the presser members they are positioned between the lugs 16 at one end of the

presser members and the strut 15 at the other end.

To spread the two members 10 and 11 apart and into firm frictional contact with the sides 5 of the bore 12 so as to prevent sliding of the holder longitudinally of the bore, spring means is provided which acts directly between the two presser members without exerting a crushing stress upon the packages positioned therebetween. This means is preferably formed from resilient sheet metal and comprises an elongated strip designated generally as 17 in Fig. 2. In the exemplary form shown herein, the strip 17 is of substantially 10 the same width as the presser members 10 and 11 and has a central portion 18 (Fig. 1) secured to the presser member 10. The portion 18 may be attached to the presser member 10 by tangs 19 struck from the presser member 10 and projecting through longitudinally spaced apertures 20 formed in the portion 18 so that the tangs may be bent back to engage the inner side of the central portion 18.

At the end adjacent the lug 16, the strip 17 is bent to form a resilient arm 21 extending transversely of the holder substantially parallel to and closely adjacent to the lug 16 and projecting toward the other presser member 11. The other end of the strip 17 is similarly bent to form a second resilient arm 22 at a point spaced from the arm 21 a distance substantially equal to the length of one package, for example, the cylindrical container 13 which holds the tar. At their ends the arms 21 and 22 are bent toward each other so as to form springs 23 extending along the other presser member 11.

The springs 23 are normally disposed at an acute angle to the presser member 11, as 40 shown in Fig. 2, and when the two presser members are compressed toward each other and placed in the bore 12 as shown in Fig. 1, the springs 23, acting through the cross-arms 21 and 22, tend to spread the presser members into firm contact with the sides of the bore.

To insure proper operation of the springs 23 the ends thereof which engage the inner arcuate surface of the presser member 11 are 50 preferably made of a corresponding arcuate form, as shown at 24 in Figs. 1 and 3, so as to hold the springs against transverse displacement relatively to the presser member 11. Since the ends of the springs 23 slide along the presser member 11 when the springs 55 are compressed, the member 11 acts as means to prevent defacing of the surface of the bore.

It will be seen that the resilient cross-arm 21 engages the lugs 16 and thus cooperates with those lugs in maintaining the container 60 12 in the holder. Because of this cooperation of the lugs 16 with the arm 21, the entire strip 17 may be made of comparatively thin gage metal. The lug 16 on the presser member 11 also aids in insuring proper operation 65 of the device since it fixes the longitudinal

position of the free end of the arm 21 with relation to the holder and causes the spring 23 of that arm to be bent in a predetermined manner.

Since the arm 22 extends across the holder intermediate the ends of the presser members, it will be seen that this arm acts as a spacer between the container 13 and the package 14. As the spring 23 of the arm 22 is bent in pressing the two members together the arm 75 22 is bowed upwardly (Fig. 1) and if the package 14 is of the proper size, it will be pressed against the strut 15, as shown in Fig. 1.

It will also be seen that as the springs 23 are bent in pressing the two members together, the ends of the springs slide along the presser member 11 and the arms 21 and 22 are bent toward each other so as to engage the end edges of the container 13 at points 80 25 adjacent to the springs 23. Thus the bending of the springs 23 to their operative positions, shown in Fig. 1, serves to fix the longitudinal positions of both of the packages 85 relative to the two presser members 10 and 11. Furthermore the engagement of the arms 10 21 and 22 with the container 13 at points adjacent to the springs 23 tends to stiffen the springs and thereby causes more efficient operation of the device. It will be apparent 90 that since the arms and springs act directly between the two presser members, the device is fixed in position in the bore by means which does not exert an undue crushing force upon the packages, and because of this fact the 100 container 13 may be made of inexpensive material, for example, of thin gage metal or of card-board.

I claim as my invention:

1. A holder for retaining packages in the 105 bore of a roll, said holder comprising a pair of substantially straight presser members adapted to extend longitudinally along opposite sides of the bore, means connecting said presser members together arranged to 110 permit relative transverse movement of the members, a strip of metal having its central portion connected to one of the presser members at points spaced longitudinally thereof and having portions extending across the 115 opposite ends of a package positioned between the presser members, the ends of said strip being bent toward each other so as to extend along the inside of the other presser member with their ends spaced a substantial 120 distance from the side of the package, said ends being adapted to urge the two presser members apart and into contact with the opposite sides of the bore.

2. A holder for retaining packages in the 125 bore of a roll, said holder comprising a pair of substantially straight presser members adapted to extend longitudinally along opposite sides of the bore and to have a container positioned therebetween, and a pair of re- 130

silent sheet metal arms connected to one of said presser members and adapted to extend transversely across the opposite ends of a container to prevent relative longitudinal displacement of the container and said last mentioned presser member, said arms having their ends bent toward each other so as to form springs projecting along the other presser member at an angle thereto, said bent ends being adapted to engage the other presser member so as to hold the two presser members firmly in engagement with the opposite sides of the bore.

3. A holder for retaining packages in the bore of a roll or the like, said holder comprising a pair of substantially straight presser members, each member being of a length substantially greater than the length of the package to be held, means connecting one end of one member to one end of the other to permit relative transverse movement of the two members, a pair of resilient arms connected to one of the members at points spaced longitudinally thereof and adapted to extend transversely across and bear against the opposite ends of a container positioned between the members, one of said arms being positioned adjacent to the free end of the member upon which it is mounted, the projecting ends of said arms being bent toward each other so as to extend along the side of the container at an angle thereto, in a position to engage the other presser member and yieldingly press the two members apart, and an end flange formed on the free end of said other presser member and adapted to engage the adjacent resilient arm to strengthen the same and prevent excessive displacement of said arm longitudinally of the holder.

40 4. A holder for retaining a pair of packages in the bore of a roll or the like, said holder comprising a pair of substantially straight presser members, each member being of a length slightly greater than the combined length of the two packages to be held, means connecting one end of one member to the corresponding end of the other to permit relative transverse movement of the two members, transversely extending means adjacent to the other end of one of the members adapted to bear one end of a container positioned between the members, and a resilient sheet metal arm connected to one of the members and extending transversely toward the other member across and adjacent to the other end of the container, the space between said arm and said connecting means being adapted to receive a second package, the projecting end of said arm being bent to extend along the side of the container at an angle thereto in a position to engage the other presser member and yieldingly press the two members apart.

65 5. A holder for retaining packages in the bore of a roll, said holder comprising a sub-

stantially straight presser member adapted to extend longitudinally along one side of the bore and to have a container positioned between it and the opposite side of the bore, a pair of resilient arms connected to said presser member and adapted to extend transversely across the ends of a container to prevent relative longitudinal displacement of the container and said presser member, said arms having their ends bent toward each other so as to project along the sides of the container at an angle thereto, said bent ends being adapted to force the presser member firmly in engagement with the side of the bore, and means to prevent defacing of the side of the bore by the ends of said arms.

6. A holder for retaining packages in the bore of a roll or the like, said holder comprising a substantially straight presser member formed from sheet metal and a strip of resilient sheet metal having one section disposed thereof along one face of said presser member, said section having a plurality of apertures formed therein, a plurality of tangs struck from said presser member extending through said apertures and clenched on the opposite side of said section, said strip at one end of said section being bent to provide a spring arm projecting from said member in a generally transverse direction and operable to force the presser member into firm contact with the bore.

In testimony whereof, I have hereunto affixed my signature.
